UNITED STATES PATENT OFFICE.

JOHN S. NEHER, OF NORTH MANCHESTER, INDIANA.

REMOVABLE SILO COVER.

Application filed March 17, 1922. Serial No. 544,549.

To all whom it may concern:

Be it known that I, JOHN S. NEHER, citizen of the United States, residing at North Manchester, in the county of Wabash and State of Indiana, have invented certain new and useful Improvements in Removable Silo Covers, of which the following is a specification.

This invention relates to improvements in 10 a removable top or cover for silos.

The main object of the invention is to provide a device of the above character which when in place on the top of the silo will be held securely against dislodgment by 15 reason of its own peculiar construction and which at the same time may be quickly removed and manipulated by the operator during the filling of the silo.

Various other objects and advantages of 20 my invention will become apparent during the continuance of the following description.

In the drawings:

Figure 1 is a view in side elevation of the 25 top portion of a silo with my improved top or cover in position thereon.

Figure 2 is a view in bottom plan of the top or cover.

Figure 3 is a view in perspective of the 30 skeleton frame of the top or cover.

The skeleton frame of the top or cover consists of body members 10 and 11 whose intermediate portion is cut away as at 12 so that they may be brought into interlocking 35 relation as clearly shown in Figure 3. When in position a pin 13 may be inserted through the interlocking parts so as to retain the members in rigid relation to each other. Between the free ends of the members 40 10 and 11 are arranged curved stays 14 which complete the frame.

Upon reference to Figure 3 it will be observed that the members 10 and 11 taper toward their end portions from a comparatively thick intermediate portion so that both their upper and lower edges 15 and 16 respectively are convex in shape. The end portions of body members 10 and 11 are cut away to form vertical shoulders as at 16' 45 and horizontal shoulders as at 17 while at

one end the body member 10 carries a trunnion 18 and at the other end a catch 19, for the bolt of a suitable lock 19'.

In order to complete the top or cover, the top of the frame is equipped with a series 55 of cover boards as shown at 20. It is to be understood of course that I am not limited to this particular form of covering and that the present embodiment merely illustrates a practical form.

When in place at the top of a silo such as designated by the numeral 21 the shoulders of the members 10 and 11 rest on the top and within the walls of the silo. An opening 27 is provided into which the 65 trunnion 18 fits while the intermediate portion of the members depends within the same as clearly shown in Figure 1. When so positioned that the lock may be properly adjusted the sliding of the cover on the top of the silo or the accidental displacement thereof will be prevented but at the same time will enable an operator to manipulate the 70 cover more freely once it has been dislodged.

It is also pointed out that a cable 23 may be attached to the top or cover as at 24 so that when the cover is dislodged it may be suspended along the side of the silo from the stud 25.

What is claimed is:

1. A top for silos comprising a frame of double convex construction, and a cover portion on said frame substantially as described.

2. A top for silos comprising a frame consisting of interlocking body members, the upper and lower edges of said body members tapering from a point intermediate the ends thereof to the outer ends of said member thereby providing a substantially double convex construction, stays arranged between 85 the ends of said body members, a cover portion for said frame, and means to lock said top in position, substantially as described.

In testimony whereof I affix my signature in presence of two witnesses.

JOHN S. NEHER.

Witnesses:

ERNEST NEHER,
HOWARD S. NEHER.
